[57] **ABSTRACT**

A closure device for closing necked dispensing tubes of the toothpaste type is provided, said device having major features which make it exceptionally convenient to use as it is constructed to be quickly opened or closed with a single hand, is non-losable from the tubes in either open or closed positions, and is semi-universal in being adapted to fit a variety of ordinary squeeze tubes of different neck diameters and types.

CLOSURE DEVICE FOR DISPENSING TUBES

RELATED APPLICATION

This application is a continuation-in-part of application Ser. No. 149,574 filed June 3, 1971 now abandoned by the present inventor.

BACKGROUND OF THE INVENTION

Closing caps of the screw type commonly used on roll up and squeeze tubes require unthreading, removal, and temporary storage somewhere, and other inconvenient steps prior to squeezing the material within the tube, and then there are several steps in replacing them. Such caps, although widely used and accepted, are further undesirable since a cap is readily lost or more often dropped so that some care must be taken to prevent subsequent contamination of the contents of the tube. Further a particular squeeze tube typically requires a particular mating cap, thereby necessitating increased kinds in inventory for manufacturers using several different squeeze tubes.

SUMMARY OF THE INVENTION

The present invention provides a closure for roll up and squeeze tubes that does not have the undesirable features of the screw type cap closure but instead is a snap-open-snap-shut finger operated valve designed to be fitted by the user or factory just once to a tube, and is never subsequently removed, or at least is not normally removed until the contents of the tube have been exhausted.

Toward the above end, it is an object of the invention to provide an improved closure device for a squeeze tube which cannot be lost from it during normal use.

Another object is the provision of an improved device for opening and closing a squeeze tube which is substantially more convenient for the user, requires few steps, is faster, and thereby encourages closing of the tube after use as well.

A further object is to provide a closure which is intrinsically cleaner in use thereby insuring improved cleanliness and freshness of the contents for future use and storage.

Yet another object of the invention is to provide a closure which fits a variety of common squeeze and roll up tubes regardless of minor differences in thread or neck diameter.

ON THE DRAWINGS

FIG. 1 is an enlarged view of a molded plastic closure device, also hereafter referred to as a stopper assembly, from a side view and in cutaway sectional view as well, and showing the device in the "open" position. The device is shown attached to a dispensing squeeze and roll up tube;

FIG. 2 is a sectional view taken along line 2-2 of FIG. 1 through the front end of the body;

FIG. 3 is an enlarged view of the device in said view and in partial cutaway section, and showing the device in the "closed" position;

FIG. 4 is similar to FIG. 3 but with the device rotated 90° about its long axis;

FIG. 5 is a sectional view taken along line 5-5 of FIG. 4 of the rear end of the body of the device;

FIG. 6 is an enlarged perspective view of the swingable cap portion of the device in "exploded" relationship with the stopper body of the device; and

FIG. 7 shows the cap attached to a tube.

AS SHOWN ON THE DRAWINGS

FIGS. 1 through 7 show the principal embodiment of the invention in various views as a closure device (stopper assembly) 11 used to valve off threaded end squeeze and roll up tubes 12 of the toothpaste type design.

In FIG. 1 is shown the stopper assembly 11 consisting of the stopper body 14 and swingable cap 16 with raised thumb lug 18, a sealing surface 19, a resilient locking skirt 20, and resilient arms 22 each hinged about one of a pair of hinge post buttons 24. In FIG. 1, the assembly 11 is shown in the open position in which the external opening 28 of the channel 25, extending through the body 14, is not covered. This cylindrical channel 25 joins another cylindrical bore not necessarily co-axially, which is the interior of the engaging skirt 32. In the partially cutaway view of the skirt 32, the threaded neck 30 of the tube 12 is engaged by the skirt 32 by interrupted threads 40 which are shown more clearly in FIG. 4. First and second sidewalls 26 and 27 are preferably of resilient plastic material, especially in the case of 26 which forms the sidewall of the engaging skirt 32. Numeral 28 refers to the external opening of the orifice channel 25.

FIG. 2 is a section through the end of the stopper body which shows the cylindrical form of the channel 25 and the front end portion of the stopper body sidewall 27.

In FIG. 3 is shown the closing device or stopper assembly 11 in the closed position in which the cap 16 has been swung about the hinge post buttons 24 to seal the channel 25 by seating the sealing surface 19 against the end 36 of the stopper body 14 and is held locked or detented in this position by the pressure exerted by the resilient plastic locking skirt 20 bearing around and against the rounded or tapered end 36 of the stopper body 14.

FIG. 4 is a view of the assembly 11 disengaged from the tube 12, rotated 90° about its axis, and partially cut away to better show the hinge or pivot post button 24 and the interrupted threads 40. The interrupted threads also shown in FIG. 5 lie on the surface inside of the engaging skirt 32, which is substantially conically tapered inside, so that the device will fit with a stronger grip a variety of tube necks; and the interrupted threads lie in a moderately different angled relationship, as shown, to the axis of the bore of the resilient engaging skirt 32 to also help adapt the device to a greater number of different threads. Universality is further aided in the embodiment shown by reducing the interrupted threads 40 to a smaller length as the conical region is reduced in diameter so that only a limited length of a given circumference is threaded whatever the diameter, thus allowing threads to be engaged along their length and also to be more easily engaged when the skirt is screwed or forced into position on the neck of the tube.

In one embodiment of the invention, the tapered skirt 32 is of an especially soft and resilient material having a smooth surface so that additional or primary mating threads are formed by cold flow or cutting by simply screwing the tapered engaging skirt onto a threaded tube neck in which case the neck acts similarly to self-threading screws.

In the view of FIG. 6 is shown the hinged cap and stopper body in exploded relationship. The hinge but-

ton post holes 50 fit over the hinge buttons 24 and are held there by an enlarged diameter 52 at the outer end of the button post. The holes then rotate about the lesser diameter 54 of the button posts.

A similar construction of one piece is possible. In this case the arms are joined directly to the stopper body at pivot connections and are of flexible material to allow rotation of the cap by flexing rather than hinging of the arms.

Note also that the cap 16 could be fastened directly to the neck of a dispensing tube as shown in FIG. 7. When the cap 16 is pivoted off the neck of tube 12, an ordinary cap can be screwed on the neck of the tube for shipment purposes.

The closure device or assembly 11 is simple to use. The engaging skirt is pushed and/or twisted into engagement with the neck of the squeeze tube; and this particular step is typically done just once during the normal use life of the dispensing tube. The contents of the tube are then discharged by pushing the cap 16 to the open position shown in FIG. 1, usually by holding the device with one hand and placing the thumb of that hand against the thumb lug 18 and displacing the cap 16, and, of course, subsequently squeezing the tube 12 to force the contents through the channel 25.

To close off the tube and its contents, the cap is then similarly thumbed back into the closed position of FIG. 3, thus sealing off the channel 25.

In both opening and closing, one hand is left free for other purposes.

The cap cannot be lost or separated from the tube in normal use since it is firmly buttoned to the device's stopper body, and therefore there is also little danger of contaminating the contents by dropping and dirtying the cap or by leaving the tube open due to loss of a cap. This feature seems especially attractive in the case of toothpaste where screw caps are frequently dropped by both adults and children down wash basin drains or onto dirty or wet floors of bathrooms.

An interesting but optional feature is possible in the case of tubes having contents in which it is desirable to dispense only a limited amount in which case a reduced diameter channel 25 (one half the diameter of the smallest diameter of skirt 32) may be used to limit the flow.

It is apparent from the foregoing description that the present invention provides a means of sealing squeeze tubes that is more convenient, generally cleaner, more foolproof, and since the invention fits a variety of tube types, more generally usable than closing means now being used to cap such tubes.

I claim:

1. A closure device for a dispensing tube having contents within and having a threaded neck portion with an opening therein, said device including in combination: a stopper body and a cap both of molded plastic construction with said stopper body having an engaging skirt at one end, said engaging skirt having an axial, substantially conical bore surrounded by a first sidewall, said first sidewall being sufficiently flexible and small at a diameter within the same to allow said engag-

ing skirt to be fitted onto the neck of the dispensing tube and consequently elastically grip said neck, and with the internal surface of said engaging skirt surrounding said conical bore having interrupted threads for further fitting and increasing the grip of said engaging skirt to a variety of different kinds of tube necks having different diameters of threads so that one design of stopper body may be used with more than one variety of dispensing tubes of unlike design, said stopper body having a second axial bore surrounded by a second sidewall and communicating with said first axial bore of said engaging skirt, said second bore extending through the stopper body and ending as an external opening at the end of said body away from said engaging skirt, said end of said body being convex, the exterior of said stopper body on the outside of said second sidewall having a pair of opposed pivot connections the axes of which lie substantially perpendicularly to the axis of said second bore and between the outer end of said engaging skirt and said external opening; said cap comprising a concave, annular sealing surface surrounded by a resilient locking skirt, and, on opposed sides two straight arms extending along the outside of said second side-wall on the stopper body and pivoted to said pivot connections on the latter, said arms positioning said locking skirt and said sealing surface on the cap for resilient deformation by said end of the stopper body when the cap is moved pivotally to a position closing the external opening of said stopper body, with said resilient locking skirt of said cap deforming in contact with said end of the stopper body sufficiently to allow said skirt to pass over said end of said stopper body and allowing said sealing surface to be brought into position over and closing said external opening, and with the subsequent reformation of said skirt of said cap resiliently about said stopper body to thereby form a detent to keep said sealing surface in position over said external opening, said detent requiring the application of a small lateral force to said cap to thereby overcome said detent, and to thereby pivot said cap at said pivot connections on the stopper body into the open position to expose said external opening and thereby allow the subsequent forcing of said contents through said external opening by squeezing said dispensing tube.

2. The closure device of claim 1 in which said interior of said engaging skirt of said stopper body is substantially conical and smooth, and of an especially soft plastic to allow the threaded neck portion of dispensing tubes to cut further mating threads in said plastic at time of attachment of said closure device to said tube.

3. The closure device of claim 1 in which said second bore is up to one-half as small as the smallest diameter of said first conical bore to thereby reduce the flow rate of tube contents from said device.

4. The closure device of claim 1 in which said interrupted threads are reduced in length toward the narrower end of said engaging skirt compared to the larger end thereof.
